UNITED STATES PATENT OFFICE.

JOSEPH S. MESNOOH, OF BROOKLYN, NEW YORK.

WINDOW-REGULATOR.

1,380,002.

Specification of Letters Patent. Patented May 31, 1921.

Application filed June 2, 1920. Serial No. 285,878.

To all whom it may concern:

Be it known that I, JOSEPH S. MESNOOH, a citizen of the United States, and a resident of the borough of Brooklyn, in the city of 5 New York, county of Kings, and State of New York, have invented certain new and useful Improvements in Window-Regulators, of which the following is a specification.

10 My invention relates to improvements in window regulators or window operating devices and an object thereof is the provision of means for opening and closing windows which will be simple in construction and 15 easy to install.

Another object of my invention is to provide a window operating device which may be readily located centrally relative to a window to be operated thereby and one 20 wherein a window may readily be replaced without the necessity of disassembling or taking down the entire apparatus.

Another object of this invention is the provision of a device of the character designated wherein means have been provided whereby the window operated by my device will always be maintained in proper position to enable the same to be moved readily through its guides at all times.

30 Other objects will appear from the detailed description which follows.

In the accompanying drawings,—

Figure 1 shows in elevation my device installed in place at a window;

35 Fig. 2 is a view of my improved apparatus taken from the rear thereof;

Fig. 3 is a section taken on the line 3—3 of Fig. 2 looking in the direction of the arrows; and

40 Fig. 4 is a section taken substantially on the line 4—4 of Fig. 3, in the direction of the arrows thereon.

Referring to the drawings in detail, 1 and 2, designate a supporting frame on 45 which my apparatus is mounted, the part 1 being secured to the part 2 by screws 3 so that the supporting frame may readily be taken apart if desired. Carried on the member 2 of the supporting frame is a face 50 plate 4, this face plate and a portion of the face 2 of the supporting frame constituting a casing. Mounted in this casing is a stud 5 on which are mounted a cam 6 and a small gear 7. The stud 5 projects to the 55 exterior of the casing as shown in Fig. 3 and is adapted to receive an operating han-

dle 8 the same being held in place thereon by a set-screw 9. The small gear 7 meshes with a large gear 10 mounted within the casing on a stud 11 this same stud carrying a cam 12, the cam 12 being provided with spaced projections 13 on the face thereof adapted to coöperate with a lug 14 formed integral with or rigidly secured to a slide 15 mounted within the casing, this slide being mounted in guides 16 and being provided with a slot 17 through which passes the stud 11 already mentioned. The slide 15 or the lug 14 thereon is in constant engagement with a spring 17' mounted within the casing this spring being under tension at all times and acting to force the slide 15 downwardly as viewed in Fig. 4 to maintain the same in engagement with the face of the cam 6. As the handle 8 is rotated, therefore, it will 70 be seen that the cam 6 will be rotated to cause the slide 15 to be reciprocated, the upward movement of this slide, as viewed in Fig. 4, carrying the lug 14 out of engagement with the face of the cam 12 so that the 75 latter is free to rotate also.

The stud 11 already referred to extends to the exterior of the casing formed by the member 2 and the cover 4 at the upper part of my apparatus and at the side of the 80 supporting frame opposite to the operating handle 8 a sprocket 18 is mounted upon the stud, this sprocket being concentric with the large gear 10 already referred to. At the lower end of the frame member 1 and 85 extending therethrough is a stud 19 the end of this stud projecting through a slot 20 in the frame member 1 and held in place by a nut or other securing means 21. Mounted on the stud 19 is a sprocket 22. This 90 sprocket is spaced from the face of the frame member 1 and on the face of the sprocket adjacent this frame member is provided a projection 23. A case member 24 is secured by means of screws or other devices 25 to the frame member 1 between the sprocket 22 and the inner face of the supporting frame and mounted wholly within this casing I provide a coil-spring 26 the inner end of which, designated 27, is secured to a lug 28 provided for that purpose in the casing while the outer end 29 is engaged by but removably secured to the lug 23 on the inner face of the sprocket 22. From this it will be seen that as the sprocket 22 is rotated the spring 26 will be wound 100 and unwound depending upon the direc-

tion of travel of the sprocket. The two sprockets 22 and 18 carry a driving member 31 comprising a sprocket chain. In order that the chain or driving member 31 may be maintained or adjusted at the proper tension I provide an adjusting screw 32 this screw having a threaded connection to a boss or other suitable device 33 secured to the supporting frame 1, the lower end of 10 the screw engaging the casing 24. By adjusting the screw 32 it will be obvious the casing 24 may be adjusted accordingly, the casing of course carrying with it the sprocket 22, movement of the stud 19 carrying 15 the sprocket being permitted by providing the slot 20 in the frame 1 as already described. The chain or driving member 31 carries a stud 34 which is secured to a plate 35 adapted to be fastened to the bottom or 20 other portion of a window to be raised and lowered the stud 34 being received by a slot 36 in the plate 35. The stud 34 has a head 37 of greater diameter than the width of the slot 36 and to facilitate the attachment 25 of the plate 35 to the driving member 31 through the medium of the stud 34 the plate 35 is made in two sections hinged to each other as at 38 and held in closed position by screws or other suitable devices 39.

30 To insure that the window regulator will be properly attached to a window to be operated thereby I provide the frame member 2 with a triangular projection 40, the apex of this triangle being exactly in line 35 with the axis of rotation of the sprockets 18 and 22 and to apply this device to a window it is merely necessary to place the apex of the triangular projection 40 at the center of the side of the window to which 40 the device is to be attached.

In use the plate 35 is first attached to a window frame, the frame comprising the members 1 and 2 with all the parts in place thereon applied in the proper position relative to a window such as 41 in Fig. 1 and then the plate 35 which it will be understood is open at this time, is placed in position on the stud 34, closed up and fastened by the fastening means 39 the stud 45 projecting through the slot 36 in the plate 35 as pointed out heretofore. The adjusting screw 32 may then be operated until the driving member or chain 31 is under the proper tension and the device is then ready 50 for operation.

It will be seen that by rotating the handle 8 the cam 6 and the gear 7 will be caused to rotate simultaneously on the stud 5, rotation of the gear 7 causing the gear 10 55 which is in constant mesh therewith, to rotate also and inasmuch as the gear 10 is mounted on the same stud as is the sprocket 18 the sprocket 18 will be caused to rotate also. At this time due to rotation of the 60 cam 6 the slide 15 will be moved upwardly

to carry its lug 14 out of the space between the projection 13 on the face of the cam 12 so that the cam will be free to rotate at this time also. Rotation of the sprocket 18, of course, causes the chain 31 to be moved to carry the plate 35 through its connection with the chain downwardly or upwardly as the case may be this plate carrying with it the plate 41. As the sprocket 22 is rotated the spring 26 will be wound up or unwound depending upon the direction of rotation of the sprocket 22. Of course as the projections on the face of the cam 6 move out of engagement with the slide 15 the latter is retracted under the action of the spring 17 so that the lug 14 on the slide 15 is alternately moved into and out of the spaces between the projections 13 on the cam 12 and the sides of the projections 13 are so formed that the projections may be forced by the lug 14 when the handle 8 is being operated, but the engagement of the lug 14 with the projections 13 is at all other times sufficient to prevent rotation of the cam 12 and therefore the same will be locked and inasmuch as this cam is non-rotatable with respect to the sprocket 18 the latter will be locked also and thereby the window locked in place at predetermined points in its travel. The locking points of the window may be varied obviously if desired by merely increasing or decreasing the number of projections 13 on the face of the cam 12. The upward movement of the plate 35 is limited by the provision of a stop 42 adjacent the top of the frame 2 which stop is adapted to be engaged by the stud 34 carried by the chain 31.

It will be obvious from the foregoing that my device is very simple in construction and very effective in operation.

It will be obvious also that by securing the coil-spring 26 in the manner described above, the gear 22 may be removed without danger of uncoiling of this spring which is of distinct advantage in making repairs or assembling this device.

It will be obvious furthermore that I have provided a very simple arrangement whereby my device as a whole may be accurately centered when applying the same to a window so that there is no danger of jamming of the window when the device is in operation.

What I claim as new is:

1. A window operating apparatus comprising a driving member, a sectional member to be attached to a window, the sections of which member are hinged together to form a slot, the driving member engaging the slot so as to be detachably secured to said sectional member.

2. A window operating apparatus comprising a chain constituting a driving member, a pin carried by said chain, a plate

- to be secured to a window, said plate being in sections hinged together so as to form a slot between them to receive said pin whereby the window may be detached from operative connection with the chain without removing the said plate from the window.
3. A window operating apparatus comprising a driving member for a window, a spring-pressed slide carrying a lug, a cam coöperating with said lug, actuating mechanism for the driving member, and a cam driven by said actuating mechanism for reciprocating said slide to move the lug carried thereby into and out of operative relation with its coöperating cam to lock the said driving member in predetermined points in the travel of the window.
4. In a window operating apparatus, the combination of a chain to be operatively connected to a window, a frame, a pair of sprockets disposed on said frame for supporting said chain, a casing on said frame, a gear therein concentric with one of said sprockets, and rotating therewith, a second gear in said casing and in mesh with the first-named gear, an operating handle for driving said second gear, a cam rotatable with said second gear, a slide actuated by said cam, and an additional cam coöperating with said slide to lock said chain when 30 the said operating handle is actuated.
5. In a window operating device the combination of a frame, sprockets carried thereby, a driving member adapted to be attached to a window and mounted upon 35 said sprockets, means for actuating said driving member, a cam rotatably mounted on said frame and concentric with one of said sprockets, a gear rigidly secured to said cam, a slidable member carrying a 40 spring-pressed lug coöperating with said cam, a rotatable cam engaging said slidable member and a gear secured thereto meshing with the second-named gear whereby rotation will be imparted to the first-mentioned 45 cam and longitudinal movement will be imparted to the slidable member to cause the lug carried thereby to be moved into and out of engagement with the first-mentioned cam to cause the driving member to be 50 locked in predetermined positions.

This specification signed this 1st day of June, 1920.

JOSEPH S. MESNOOH.
